3-HYDRAZINOPYRIDAZINES HAVING
HYPOTENSIVE ACTIVITY

ABSTRACT OF THE DISCLOSURE

New 3-hydrazino-6-substituted amino-pyridazines of the formula:

wherein R' is hydrogen, lower alkyl or hydroxy-lower alkyl, while R'' is lower alkyl, hydroxy-lower alkyl or phenyl, R' and R'' together forming an optionally lower alkyl substituted heterocyclic ring with one or two heteroatoms, such as morpholino, piperidino and 4-methyl-1-piperazino. The compounds have a high degree of hypotensive activity.

This invention is concerned with new pharmacologically active compounds, and with a method for preparing them.

More particularly, the compounds hereinbelow disclosed are 3,6-disubstituted pyridazines of the general formula:

wherein R' is a member selected from the class consisting of hydrogen, lower alkyl and hydroxy-lower alkyl groups, R'' is a member selected from the class consisting of lower alkyl, hydroxy-lower alkyl and phenyl groups, R' and R'' taken together form an optionally lower-alkyl substituted heterocyclic ring with 1-2 heteroatoms. When, for instance, the heterocyclic ring is morpholine, the compound is 3-hydrazino-6-morpholino-pyridazine.

The compounds of the invention have proved useful as hypotensive agents. For instance, 3-hydrazino-6-morpholino-pyridazine (A), 3-hydrazino-6-piperidino-pyridazine (B) and 3-hydrazino-6-bis-(2-hydroxyethyl)-amino-pyridazine (C) were administered by intravenous route to dogs anesthetized with 35 mg./kg. of sodium pentobar-

2

bital. The results obtained for the hypotensive effect are given in Table 1.

TABLE 1

Compound	No. of dogs	Dose, mg./kg.i.v.	Decrease of blood pressure, mm. Hg
A-----	3	10	-108
	2	5	-55
	2	1	-70
	1	0.5	-95
B-----	1	0.1	-40
	1	1	-105
	2	0.5	-55
C-----	3	0.1	-47
	1	10	-80
	1	1	-90
	1	0.1	-90
	1	0.01	-20

It may be seen that said compounds have a strong, gradual and lasting hypotensive effect; no alteration of breath was noted. The same compounds were tested also on rats with renal hypertension induced by Grollman's procedure described in Proc. Soc. Exptl. Biol. Med., 57, 102 (1944). The compound was administered once a day for 5 days, per os, in aqueous solution. Compound A was tested in doses of 5, 2, 1, 0.5, 0.25 mg./kg.; compound B in doses of 1, 0.25, 0.1 mg./kg.; compound C in doses of 1, 0.5, 0.25, 0.1 mg./kg. Compound A showed a strong and lasting antihypertensive effect at every dose. Compound B showed remarkable and lasting effect at the dose of 1 and 0.25 mg./kg., a minor action at 0.1 mg./kg. Compound C was effective at all doses higher than 0.1 mg./kg. A comparison was also carried out between compound A and the well-known hypotensive agent hydralazine. Both compounds were tested on rabbits anesthetized with sodium pentobarbital.

TABLE 2

Compound	No. of rabbits	Dose, mg./kg. i.v.	Starting blood pressure mm. Hg	Modifications in blood pressure, mm. Hg after minutes—			
				10	30	60	120
A-----	2	0.2	97	-34	-41	-43	-39
Hydralazine-----	2	0.2	104	-14	-27	-31	-28
A-----	4	0.1	116	-35	-49	-47	-44
Hydralazine-----	2	0.1	123	-9	-19	-20	-20
A-----	8	0.05	104	-15	-27	-28	-7
Hydralazine-----	7	0.05	106	-11	-17	-18	-102

It may be seen that the remarkable hypotensive effect is prolonged, also with very low doses, beyond two hours. Compound A always shows a greater activity than hydralazine at equal doses.

The preparation of the compounds of the invention runs through two reaction steps. In the first step, the starting 3,6-dichloro-pyridazine I, by reaction with about two equimolecular amounts of a primary or secondary amine, in an anhydrous organic solvent, gives a mono-amino derivative, which is hereinbelow represented with formula II. By refluxing compound II with hydrazine hydrate the corresponding hydrazino derivative III is obtained as follows:

The following examples illustrate the invention.

EXAMPLE 1

Preparation of 3-hydrazino-6-morpholino-pyridazine

An amount of 149 g. (1 mole) of 3,6-dichloropyridazine and 174 g. of morpholine (2 moles) are mixed in 750 ml. of anhydrous ethanol. The mixture is refluxed for 2 hours: the two compounds completely dissolve. The solution is cooled and the precipitated solid is separated by filtration. The precipitate is taken up with water and again filtered. The collected solid is crystallized from water, thus obtaining 174 g. of pure product (yield 75%), M.P. 138-140° C. This product is 3-chloro-6-morpholino-pyridazine.

Fourty grams of the above product are suspended in 370 ml. of 98% hydrazine hydrate. The mixture is refluxed for two hours, then it is cooled, and the formed precipitate is collected, washed with about 50 ml. of hydrazine hydrate and recrystallized from toluene; yield 28 g. (75%), M.P. 145-150° C.

The dihydrochloride, prepared by bubbling HCl in a diethyl ether solution of the free base and collecting the precipitate, melts at 236° C.

EXAMPLE 2

Preparation of 3-hydrazino-6-bis-(2-hydroxyethyl)-amino-pyridazine

A solution of 61 g. of 3,6-dichloro-pyridazine and 87 g. of bis-(2-hydroxyethyl)-amine in 750 ml. of cyclohexanol is refluxed for 3 hours. The solvent is then removed in vacuo, and the residue is taken up in 150 ml. of water; this solution is extracted twice with petroleum ether in order to remove the still present small quantity of cyclohexanol. The solution is then salted with sodium chloride and extracted with ethyl acetate. The obtained solution, after drying over sodium sulfate, is concentrated to dryness, and the residue is crystallized from isopropyl alcohol. Sixty grams of 3-chloro-6-bis-(2-hydroxyethyl)-amino-pyridazine are thus obtained (yield 70%), M.P. 96-98° C.

Eleven grams of this product are mixed with 300 ml. of 98% hydrazine hydrate and refluxed for two hours. The mixture is allowed to stand for 12 hours at room temperature, then it is concentrated in vacuo and the residue is taken up with hot ethanol. When this solution is cold, the precipitate is separated by filtration, and from the filtrate the solvent is removed in vacuo. The residue is dissolved in 60 ml. of hot isopropyl alcohol and then filtered on Fuller's earth; the product precipitates from the filtrate by adding a diethyl ether solution of hydrogen chloride. The product is dissolved in anhydrous ethanol, from which is then recrystallized. The product is 3-hydrazino-6-bis-(2-hydroxyethyl)-amino-pyridazine dihydrochloride (the free base, when isolated by usual procedure, is not stable). Yield 9.8 g. (66%), M.P. 187.5-188.5° C.

EXAMPLE 3

Preparation of 3-hydrazino-6-(N-phenyl-N-methyl)-amino-pyridazine

Three grams of 3,6-dichloropyridazine and 4.28 g. of N-methyl-aniline are dissolved in 15 ml. of boiling butanol and refluxed for three hours. The solvent is then removed in vacuo to dryness, and the residue is taken up with water; this solution is extracted several times with diethyl ether. The obtained solution yields, by removing the organic solvent in vacuo, the crude product, which is

crystallized from diisopropyl ether. It is 3-chloro-6-(N-phenyl-N-methyl)-amino-pyridazine, yield 3.9 g. (75%), M.P. 89-91° C.

An amount of 1.5 g. of this product is dissolved in 26 ml. of 98% hydrazine hydrate. The mixture is refluxed for 10 hours, then the solvent is distilled in vacuo to dryness. The residue is taken up with CHCl_3 and washed twice with a saturated aqueous solution of sodium chloride. The organic layer is then dried and chloroform is distilled off. The oily residue is dissolved in methanol and treated with a diethyl ether solution of hydrogen chloride. On cooling, the solution yields a precipitate which is recrystallized from ethanol: it is 3-hydrazino-6-(N-phenyl-N-methyl)-amino-pyridazine dihydrochloride. Its weight is 1.3 g. (65%), M.P. 206-208° C. The free base can be isolated by usual procedures, f.i. by adding an alkali hydroxide or carbonate to the aqueous solution of the dihydrochloride and extracting with diethyl ether. However, the free base is scarcely stable at ordinary temperature and decomposes promptly on heating.

EXAMPLES 4-5

The following compounds were prepared as shown in Example 1:

- 25 (4) 3-Hydrazino-6-piperidino-pyridazine, yield 75%, M.P. 140-145° C.
 (5) 3-Hydrazino-6-(4-methyl - piperazino) - pyridazine, yield 70%, M.P. 165-167° C.

30 We claim:

1. A compound selected from a 3,6-disubstituted pyridazine of the formula:

35 wherein R' is a member selected from the class consisting of hydrogen, lower alkyl and hydroxy-lower alkyl groups, R'' is a member selected from the class consisting of lower alkyl, hydroxy-lower alkyl and phenyl groups, and wherein R' and R'' taken together with the N-atom form a member of the group consisting of morpholino, piperidino and 4-methyl-piperazino, and its non-toxic mineral acid addition salts.

40 2. A compound as in claim 1, wherein the 3,6-disubstituted pyridazine is 3-hydrazino-6-bis-(2-hydroxyethyl)-amino-pyridazine.

3. A compound as in claim 1, wherein the 3,6-disubstituted pyridazine is 3-hydrazino-6-bis-(2-hydroxyethyl)-amino-pyridazine hydrochloride.

45 4. A compound as in claim 1, wherein the 3,6-disubstituted pyridazine is 3-hydrazino-6-morpholino-pyridazine.

50 5. A compound as in claim 1, wherein the 3,6-disubstituted pyridazine is 3-hydrazino-6-morpholino-pyridazine hydrochloride.
